UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed September 29, 1921, Serial No. 504,062. Renewed October 8, 1923.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to sound-deadening 10 devices for combined typewriting and computing machines, and is herein illustrated as applied to the type of machine disclosed in the patent to Hart, No. 1,270,411, dated June 25, 1918.

15 For deadening the sounds arising in the operation of the machine, this invention provides a sound-deadening cabinet which completely encloses the noise-producing parts of the machine while permitting ready access thereto. For this purpose, the sound-deadening cabinet may comprise two sections in the form of a main casing to be applied to the upper or typewriter portion of the machine, and an auxiliary casing for the lower 25 portion of the machine. Slots and openings are provided in the cabinet for permitting various operating mechanisms, such as levers, keys, and other devices, to project outside of the cabinet, so that they may be operated without necessitating removal of any 30 part of the casing, sound-deadening means being provided for closing the slots and openings to prevent escape of sound therethrough.

35 It is a feature of this invention to provide means whereby one of the casings of said cabinet may be applied to the machine and positioned relatively thereto, and means whereby the other of said casings may be positioned relatively to said first casing.

Another feature is the construction of the parts of the cabinet in such manner as to permit it to be readily applied to or removed from the machine.

45 A further feature is the provision of various removable sections on the casings to allow access to various portions of the machine without removing the casings.

50 A further feature is the provision of a sound-deadening lining for the computer case or portion to prevent transmission of sound vibrations therethrough and to provide closures for openings in the case,

through which openings various operating devices extend to the outside of the casing. 55

Other features and advantages will hereinafter appear.

In the accompanying drawings,

Figure 1 is a perspective view of the sound-deadening cabinet applied to an Underwood bookkeeping machine. 60

Figure 2 is a side view thereof.

Figure 3 is a front elevation, partly sectioned, of the device shown in Figure 1.

Figure 4 is a side view, vertically sectioned, of the device shown in Figure 1. 65

Figure 5 is a plan view, with parts broken away, of the auxiliary casing applied to the lower portion of the machine, the typewriter portion of the machine, which is arranged above the computer portion, having been removed. 70

The Underwood standard bookkeeping machine, to which the sound-deadening cabinet is applied, may be of the general type 75 disclosed in said patent to Hart, No. 1,270,411, and comprises a typewriter-frame 10 mounted upon a computer-case 11, a base 12 upon which said case is mounted, and various operating mechanisms, such as a driving motor 15 and clutch 16 suspended beneath said base, said frame and case being suitably mounted, preferably by lugs 17 fixed to the base, upon a stand 20 which may be of the type disclosed in the patent to 80 Hart, No. 1,063,878, dated June 3, 1913. The typewriter-frame comprises a forward extension 21, in which are positioned alphabet-keys 22 and numeral-keys 23, as in the Underwood standard typewriting machine. The numeral-keys and alphabet-keys 85 operate type-bars 24 to cause types 25 carried thereby to print against the platen 26 forming part of a carriage 27 mounted for letter-feeding movement upon a front rail 28 and a rear rail 29 on the typewriter-frame 10. A space is formed between the typewriter portion and the computer-case, in which space operate denominational tabulator keys 30, subtract key 31, and the non-compute key 32 in a guide-plate 33 which 90 closes said space at the front.

95 The carriage is provided with selecting dogs 35 which, upon entering a computing zone, are lifted by a cam-roller 36 into effective relation with jacks 37, the travel of 100 105

the carriage to the left bringing said dogs into successive engagement with the jacks to lift each successive jack. The raising of each jack thrusts forwardly a corresponding computing bar 34 within the computer-case through the action of a thrust-bar within the casing 38, a lever 39 and a transposition linkage 40, whereby the computing bars will be operated forwardly from left to right in the order in which the numerals are typed; although the jacks are raised successively from right to left, the transposition linkages operating bell-crank 41 connected with said computing bars. When the computing bars are moved forwardly, indexing pins 42 carried by said computing bars, and corresponding to the numerals from "1" to "9," are brought into operative position directly beneath pin-setting bars 43 operated by the numeral-keys and normally positioned forwardly of pins 42. The means for operating said pin-setting bars by the numeral-keys comprises a stem 46 carried by each numeral-key, said stem operating a rock-shaft 47 through an arm 48 fixed to the rock-shaft, each pin-setting bar being operated by its own rock-shaft, and each rock-shaft being operated by one of the numeral-keys. Operation of a numeral-key, when the carriage is in a computing zone, thus operates a pin-setting bar to depress the proper pin on the denominational thrust-bar which is then in forward position. When a number which is to be run into a computing register has been fully typed, and the pins have been set on the computing bars of proper denominations, said number may be run into the register 50 at the front of the computer-case by operating the computing bars forwardly through distances corresponding to the values of the depressed pins.

For driving the computing bars forwardly, there is provided a general operator 51 which may be of the type disclosed in the patent to Hanson, No. 1,278,812, dated September 10, 1918, and comprises a cross-bar or engaging portion 52, which may be moved forwardly to engage the lower ends of the set of depressed indexing pins, to drive the computing bars forwardly distances corresponding to the values of the depressed pins.

The computing bars 34 are provided at their forward ends with racks 53 meshing with pinions (not shown) associated with the dial-wheels 55 to rotate the latter through distances proportional to the movement of the computing bars; the numerals on the peripheries of the dial-wheels being readable through a sight-opening 56 in a front cover-plate 57 of the computer-case, the front cover-plate 57 forming a continuation of the guide-plate 33.

The general operator may be actuated by a handle 59 on a rock-shaft 60, the rock-

shaft having two gear-sectors 61 secured thereto, which mesh with intermediate pinions 62 engaging racks 63, formed on guide-bars 64 of the general operator to reciprocate the latter, the cross-bar 52 being secured to the guide-bars 64 by brackets or arms 65.

The general operator may be reciprocated by the electric motor 15 instead of the handle 59. The motor may be normally at rest and may be started manually, or automatically as indicated in the patent to Thornton, No. 1,283,360, dated October 29, 1918, after the last digit is written in the column. To start the motor manually, there is provided a key 67, which may be depressed against the tension of a return-spring (not shown) to operate a rearwardly-extending lever 68, to depress the outer end of a horizontally-disposed lever 69 extending inwardly from the side of the machine, to raise the inner end of said lever, said inner end being effective to actuate a trip-pin 70 to start the motor and render the clutch 16 effective.

The clutch-mechanism and the motor-switch-operating mechanism may be like that disclosed in the patent to Wood, No. 1,299,646, dated April 8, 1919, in which the rendering of the clutch effective reciprocates an arm or projection 71 engaging a fork 72 secured to one of the guide-bars 64 of the general operator 51. Thus, it will be seen that, when the motor makes a revolution, the general operator is reciprocated, or, in other words, is caused to make a cycle, the forward stroke of the general operator being effective to drive the computing bars to run in the indexed number, the rearward stroke of the general operator being effective to restore the computing bars to their normal positions; the computing bars being provided for this purpose with projections 73 which are engaged by the cross-bar 52 of the general operator on its return stroke. The indexing pins 42 are restored by pin-restoring mechanism including a platform 74 which is actuatable by the general operator during the latter part of its return stroke, as shown in the above-mentioned Hanson patent.

When the cycle is completed, the circuit through the motor is broken and the clutch rendered ineffective, as is disclosed in said patent to Wood.

It will be understood that, when the general operator is to be reciprocated by the operating handle 59, the motor-drive may be disconnected by lowering the projection 71 of the clutch-mechanism out of engagement with the fork 72 on the guide-bar of the general operator, as disclosed in the patent to Hart, No. 1,212,895, dated January 16, 1917. For this purpose, there is provided a clutch-device 75 in the form of a bell-crank, one arm 76 of which supports the clutch-mechanism-case, and the other end

77 of which is swingable to rotate said case about the motor-shaft. By rotating the clutch-device, the clutch-mechanism-case is swung about the motor-shaft, to bring the 5 projection 71 out of engagement with the fork.

The machine may be provided with a key 79 which, when depressed, serves to start the motor and render effective a clutch 80, 10 so that said motor operates a belt-and-pulley system 81 to rotate a pinion 82 which meshes with a rack 83 on the carriage to return the carriage to starting position. The details 15 of the carriage-return mechanism may be as shown in the patent to Hart, No. 1,238-, 908, dated September 4, 1917.

To deaden the sounds arising in the operation 20 of the machine, there is provided a cabinet which completely encloses the noise-producing parts of the machine, while permitting the ordinary operations of the machine to be carried on without removing the casing, and giving ready access to the machine when desired. For this purpose, the 25 cabinet consists of a main casing 85 to enclose the typewriter portion and a portion of the computer-case, and an auxiliary casing 86 to enclose the mechanism below the computer-case.

The auxiliary casing comprises a body-part 30 87 and a cover-part 88, the latter being provided with an opening large enough to receive the computer-case and permit passage therethrough of mechanisms, such as the lever-enclosing casing 38, at the rear of the machine, and the carriage-return belts 35 81 which extend from below the computer-case upwardly to the typewriter portion. The cover-part 88 may be of a single piece 40 which is slid downwardly over the typewriter portion until it rests upon the supporting lugs 17 which pass through cut-out portions 89 therein; or, if desired, it may be formed of two pieces 90, 91, which are slid 45 upon the machine from the front and rear, as shown, or from two sides. The two portions of the cover-part may be fastened together in any suitable manner, as by overlapping sides 92, 93, through which screws 50 94 may be passed (see Figure 5). The mechanism beneath the computer-case is effectively enclosed by applying the body-part to the cover-part. Said body-part is preferably curved to enclose the mechanism below 55 the computer-case within a minimum amount of space, and is of such size that it may be slid rearwardly into stand 20, which is open from front to rear, and then raised slightly until its upper edges 95 overlap the 60 lower edges 96 of the cover-part (Figure 4), to which it may be fastened, as by screws 97. To allow ready access to the mechanism within the auxiliary casing, the body-part thereof may be provided with removable 65 sections, such as a back plate 98 and side

plates 99, said plates overlapping the other portions of the body-part, to which they may be fastened, as by screws. To permit the clutch-device 75 to be operated from outside the casing, a slot is provided in the 70 body-part and preferably in one of the removable sections 99 to give access to said clutch mechanism, through which said device extends, said slot being closed by sound-deadening cushions 100, 101 fixed on either 75 side thereof. The conductor 102, which supplies current for the motor, passes through the casing, the opening thus formed being closed preferably by a plate 103. The entire auxiliary casing may be lined with sound-deadening material 105, thus preventing 80 transmission of sound vibrations therethrough. The auxiliary casing may be positioned upon the machine by means of the cut-out portions 89 through which the supporting lugs extend, and, more accurately, by abutments 110 which may be of sound-deadening material fixed to the interior of 85 the casing, and which contact at the front, sides, and rear with the base 12 which supports the typewriter portion and the computer-case, the abutments at the rear being mounted preferably on depending brackets 111 fixed to the cover-part 88. The main casing is mounted upon the auxiliary casing, 90 and may be positioned relatively thereto as by devices which may be in the form of lugs or hooks 112 fixed to the auxiliary casing and engaging flanges 113 at the base of the main casing, said flanges serving to support 95 the main casing upon the auxiliary casing.

The main casing comprises a body-part 115 and a cover-part 116 hinged at the rear to said body-part, said body-part having a 100 large front opening permitting the passage of the typewriter portion and computer-case therethrough. The body-part terminates at the front adjacent the front of the typewriter-frame, the forward extension 21 and the forward portion of the computer-case extending forwardly from the main casing. For closing the front opening, there is provided a removable front plate 117 mounted upon the body-part. The latter conforms 105 closely to the typewriting machine and the computer-case near the base, but flares outwardly and upwardly at the sides to form lateral extensions in which the typewriter-carriage may operate to the right and left. To allow access to the mechanism at the 110 rear of the typewriter portion, the body-part may be provided with a removable back plate 120.

To enclose the typewriter portion at the top, there is provided the cover-part 116 115 hinged to the body-part at 121, said cover-part comprising side walls 122 co-operating with and overlapping the extreme sides of the body-part extensions, and a ceiling 123 which slopes downwardly and forwardly, 120 130

4

and in which is positioned a window 124 for permitting the machine and the typing in the interior of the casing to be viewed. Said ceiling terminates in a short front wall 125 some distance above the top of front plate 117 to form a slot, through which extend, from the carriage, the various operating handles, such as the line-space handle 126, the carriage-return finger-piece 127, and 10 the carriage-release lever 128, so that said carriage may be operated from outside of the casing. For closing all of the slot not occupied by the carriage-operating levers, there may be provided co-operating sound-deadening cushions 129, 130 mounted on the front wall and front plate, respectively.

With the main casing and auxiliary casing in position on the machine, it will be apparent that the machine is completely 20 enclosed, with the exception of the forward extension and the forward portion of the computer-case. The exposure of these portions gives access to the typewriter-keys 22 and 23, the tabulator keys 30, the subtract key 31, the non-compute key 32, the usual error keys 132 and star keys 133, the registers visible through a window 135, the handle 59 for operating the general operator, the key 79 for operating the automatic carriage-return, and the key 67 for starting the motor. In addition, there are also exposed the handles projecting from the carriage and the device 75 for operating the clutch to effective and ineffective positions. It will 30 thus be seen that all of the ordinary operations of the machine can be carried out without removing the main casing or the auxiliary casing. The openings, through which extend the various carriage-operating handles, the device for controlling the position of the clutch, and the conductor supplying current to the motor, are closed to prevent escape of sound therethrough in the manner hereinbefore described. The portion of the 40 computer-case which extends outside of the main casing and auxiliary casing may be lined with sound-deadening material 136 (Figure 4), through which extend the various keys and levers at the front of the computer-case enumerated above. The lining of the computer-case may be extended upwardly, the upper extension 137 reaching 50 guide-plate 140 in which operate the typewriter key-levers, and being provided with slits in which the tabulator key-levers operate. The portion of the front plate above the keys 23 may also be lined with sound-deadening material 141. It will thus be apparent that substantially every outlet from 60 the main casing, auxiliary casing, and computer-case is closed against the escape of sound.

The machine may be provided with a sign 143 for indicating the state of the machine with respect to addition or subtraction.

tion, as disclosed in the patent to Kupetz, No. 1,856,072, dated October 19, 1920. To render this sign visible when the cabinet is in position on the machine, the main casing may be provided with a cut-out portion or 70 window 144, which is independent of the window 124 and is located below it and in the body-part 115 of the main casing.

No claim is made herein for any feature that is disclosed in the application of G. W. Campbell No. 500,514. The claims herein are limited to features not disclosed in said Campbell application. This application covers improvements upon the disclosures of application No. 381,259, Patents No. 1,499,709, No. 1,519,224, No. 1,519,645, and applications No. 468,257, No. 469,114, No. 471,173, No. 473,018, No. 475,061, No. 476,765, No. 478,231, No. 485,521 and No. 490,505.

The cover 116 of the casing for the typewriter section may be raised by means of a finger-piece 150 on said cover. The front wall 125 of the cover is provided with abutments 151 to engage the upper edge of the releasable plate 117, so that the latter may 85 support the cover at the front.

Variations may be resorted to within the scope of the invention, and portions of the improvements may be used without others.

Having thus described my invention, I 95 claim:

1. The combination with a combined typewriting and computing machine having a typewriter with a keyboard, a computer, computer-operating mechanism under said computer, and a support on which said computer rests and below which said mechanism is supported, of sound-deadening means comprising a lower casing having a top 100 surrounding the base of the computer and overlying said support to be supported thereby and a bottom beneath said mechanism and connected with said top, and an upper casing comprising a body having back and side walls resting on the top of the lower casing and enclosing the rear and sides of the typewriter and the computer, a front wall to close the front of the body around the keyboard and the front part of the computer and resting on the top of the lower casing, and a cover hinged to the body at the rear to close said body when in lowered position.

2. The combination with a combined typewriting and computing machine comprising a typewriter and a computer having a case on which said typewriter rests and extending to the front of the typewriter to expose a register of the computer, a stand having a top to support the computer case, and computer-operating mechanism supported by said stand beneath its top, of sound-deadening means comprising a lower sound-deadening casing for said operating mechanism supported by the edges of the stand around 110 115 120 125 130

- the computer case, and an upper sound-deadening casing comprising a body to rest on the upper part of the lower casing and having a back wall, side walls and a front 5 plate through which projects the keyboard of the typewriter and the front portion of the computer case, and a cover for said body.
3. A sound-deadening cabinet for a machine comprising a typewriter, a computer supporting the typewriter and controlled thereby, and computer-operating mechanisms beneath said computer, said cabinet comprising a main casing for said typewriter and computer, and an auxiliary casing 10 for said mechanisms beneath said computer, said main casing resting upon said auxiliary casing.
4. A sound-deadening cabinet for a machine comprising a typewriter, a computer beneath the typewriter and controlled thereby, and computer-operating mechanisms beneath said computer, said cabinet comprising a main casing for said typewriter and computer, an auxiliary casing for said mechanisms beneath said computer, said auxiliary casing being formed in sections, so that it may easily be assembled around 15 the base of the computer, and means for supporting said auxiliary casing upon said machine, said main casing resting upon said auxiliary casing.
5. The combination with a combined typewriting and computing machine comprising a typewriter and a computer having a case 20 on which said typewriter rests and extending to the front of the typewriter to expose a register of the computer, a stand having a top to support the computer case, and computer-operating mechanism supported by said stand beneath its top, of sound-deadening means comprising a lower sound-deadening casing for said operating mechanism supported by the edges of the stand around 25 the computer case, and an upper sound-deadening casing comprising a body to rest on the upper part of the lower casing and having a back wall, side walls and a front plate 30 through which projects the keyboard of the typewriter and the front portion of the computer case, a cover for said body, and a sound-deadening lining for the front part of the computer case.
6. The combination with a combined typewriting and computing machine comprising a typewriter having a forward extension with key-levers therein and a computer having a case on which said typewriter rests and extending to the front of the typewriter 35 to expose a register of the computer, a stand having a top to support the computer case, and computer-operating mechanism supported by said stand beneath its top, of sound-deadening means comprising a lower sound-deadening casing for said operating 40 mechanism supported by the edges of the stand around the computer case, and an upper sound-deadening casing comprising a body to rest on the upper part of the lower casing and having a back wall, side walls and a front plate 45 through which projects the keyboard of the typewriter and the front portion of the computer case, a cover for said body, and a sound-deadening lining for the front part of the computer case.
7. A sound-deadening cabinet for a machine comprising a typewriter, a typewriter-controlled computer beneath the typewriter, a stand on which said computer rests, a computer-operating motor-device beneath the computer, and a downwardly-extending 50 handle for controlling the connection between the motor-device and the computer, said cabinet comprising a casing enclosing the motor-device and comprising an upper part having an opening to permit the passage of the computer therethrough, and a lower part connected with the lower edge of the upper part and having a slot to receive said handle when the lower part is placed beneath the upper part and lifted into engagement therewith.
8. A sound-deadening cabinet for a machine comprising a typewriter, a typewriter-controlled computer beneath the typewriter, a stand on which said computer rests, a computer-operating motor-device beneath the computer, and a downwardly-extending handle for controlling the connection between the motor-device and the computer, said cabinet comprising a casing enclosing 55 the motor-device and comprising an upper part having an opening to permit the passage of the computer therethrough, a lower part connected with the lower edge of the upper part and having an opening to give 60 access to said motor-device, and a cover for said opening having a slot therein to receive said handle.
9. A sound-deadening cabinet for a machine comprising a typewriter, a typewriter-controlled computer beneath the typewriter, a stand on which said computer rests, a computer-operating motor device beneath the computer, and a downwardly-extending handle for controlling the connection between the motor-device and the computer, said cabinet comprising a casing enclosing 65 the motor-device and comprising an upper part having an opening to permit the passage of the computer therethrough, a lower part connected with the lower edge of the upper part and having an opening to give 70 access to said motor-device, a cover for said opening having a slot therein to receive said handle, and inwardly-extending flexible lips 75

on the cover at each side of the slot to seal the slot around the handle.

10. A sound-deadening assemblage for a machine comprising a typewriter having a keyboard, a typewriter-controlled computer beneath the typewriter and having a case with a register extending beyond the front of the typewriter, and operating members extending through slots in the ceiling of the case and at the front thereof, said assemblage comprising a cabinet enclosing said machine around the keyboard and the register, and a layer of sound-deadening material lining the front wall of the computer case and a portion of the ceiling thereof outside of said cabinet, the layer of sound-deadening material serving to prevent the escape of sound through said slots.

11. A sound-deadening assemblage for a machine comprising a typewriter having a keyboard, a typewriter-controlled computer beneath the typewriter and having a case with a register extending beyond the front of the typewriter, and operating members extending through slots in the ceiling of the case and at the front thereof, said assemblage comprising a cabinet enclosing said machine around the keyboard and the register, a layer of sound-deadening material lining the front wall of the computer case and a portion of the ceiling thereof outside of said cabinet, the layer of sound-deadening material serving to prevent the escape of sound through said slots, and a layer of sound-deadening material extending upwardly from the sound-deadening material in the ceiling of the computer case into the typewriter at the rear of the keyboard.

40 12. A sound-deadening cabinet for a machine comprising a typewriter, a computer beneath the typewriter and controllable thereby, and computer-operating mechanisms beneath said computer, said cabinet comprising a main casing for said typewriter and computer, an auxiliary casing for said mechanisms, said main casing resting upon said auxiliary casing, and means for positioning said casings with respect to the machine.

45 13. A sound-deadening cabinet for a machine comprising a typewriter, a computer beneath the typewriter and controllable thereby, and computer-operating mechanisms beneath said computer, said cabinet comprising a main casing for said typewriter and computer, an auxiliary casing for said mechanisms, said main casing resting upon said auxiliary casing, means for positioning one of said casings with respect to the machine, and means for positioning the other of said casings with respect to the first casing.

50 14. A sound-deadening cabinet for a machine comprising a typewriter, a computer

beneath the typewriter and controllable thereby, and computer-operating mechanisms beneath said computer, said cabinet comprising a main casing for said typewriter and computer, an auxiliary casing for said mechanisms, said main casing resting upon said auxiliary casing, means for positioning said casings with respect to the machine, and means for positioning the main casing with respect to the auxiliary casing.

55 15. A sound-deadening cabinet for a machine comprising a typewriter, a computer beneath the typewriter and controllable thereby, and computer-operating mechanisms beneath said computer, said cabinet comprising a main casing for said typewriter and computer, an auxiliary casing for said mechanisms, said main casing resting upon said auxiliary casing, means for positioning said auxiliary casing with respect to the machine, comprising abutments carried by said auxiliary casing and engaging said machine, and means for positioning said main casing with respect to the auxiliary casing.

60 16. A sound-deadening cabinet for a machine comprising a typewriter, a computer beneath the typewriter and controllable thereby, and computer-operating mechanisms beneath said computer, said cabinet comprising a main casing for said typewriter and computer, an auxiliary casing for said mechanisms, said main casing resting upon said auxiliary casing, means for positioning said auxiliary casing with respect to the machine, and means for positioning said main casing with respect to the auxiliary casing, said last-named means comprising hooks on said auxiliary casing for engaging said main casing.

65 17. A sound-deadening cabinet for a machine comprising a typewriter, a computer beneath the typewriter and controllable thereby, computer-operating mechanisms beneath said computer, and supporting lugs whereby said machine may be supported upon a stand, said cabinet comprising a main casing for said typewriter and computer, and an auxiliary casing for said mechanisms, said auxiliary casing being supported upon said supporting lugs and said main casing resting upon said auxiliary casing.

70 18. A sound-deadening cabinet for a machine comprising a typewriter, a computer beneath the typewriter and controllable thereby, computer-operating mechanisms beneath said computer, and supporting lugs whereby said machine may be supported upon a stand, said cabinet comprising a main casing for said typewriter and computer, and an auxiliary casing for said mechanisms, said auxiliary casing having cut-out portions for receiving said support.

ing lugs and being formed of sections so that it may be assembled around said lugs without detaching the lugs from the stand, said main casing resting upon said auxiliary 5 casing.

19. A sound-deadening cabinet for a machine comprising a typewriter, a computer beneath the typewriter and controllable thereby, computer-operating mechanisms 10 beneath said computer, and supporting lugs whereby said machine may be supported upon a stand, said cabinet comprising a main casing for said typewriter and computer, an auxiliary casing for said mechanisms, said auxiliary casing resting upon said supporting lugs, said main casing resting upon said auxiliary casing, means for 15 positioning said auxiliary casing with respect to the machine, and means for positioning the main casing with respect to the auxiliary casing.

20. A sound-deadening cabinet for a machine comprising a typewriter, a computer beneath the typewriter and controllable 25 thereby, computer-operating mechanisms beneath said computer, and supporting lugs whereby said machine may be supported upon a stand, said cabinet comprising a main casing for said typewriter and computer, an auxiliary casing for said mechanisms, said auxiliary casing resting upon said supporting lugs, said main casing resting upon said auxiliary casing, means for 30 positioning said auxiliary casing with respect to the machine, comprising abutments carried by said auxiliary casing and engaging said machine, and means for positioning said main casing with respect to the auxiliary casing, comprising hooks on said auxiliary casing for engaging said main casing.

21. A sound-deadening assemblage for a machine comprising a typewriter having a keyboard, a typewriter-controlled computer beneath the typewriter and having at the front a register extending beyond the front of the typewriter, and computer-operating mechanism under said computer, said assemblage comprising a cabinet having an upper section with a front wall having a cutout through which the keyboard and register project, and a lower section having a ceiling with an opening through which the forward part of the computer extends, and a sound-deadening lining for the part of the computer projecting from said cabinet.

22. A sound-deadening assemblage for a machine comprising a typewriter having a keyboard and a key-lever comb at the rear of the keyboard, a typewriter-controlled computer beneath the typewriter and having at the front a register extending beyond the front of the typewriter, and computer-operating mechanism under said computer, said assemblage comprising a cabinet having an upper section with a front wall having a

cutout through which the keyboard and register project, and a lower section having a ceiling with an opening through which the forward part of the computer extends, a sound-deadening lining for the part of the 70 computer projecting from said cabinet, and a sheet of sound-deadening material extending upwardly from said sound-deadening lining to engage the lower part of said comb.

23. A sound-deadening cabinet for a machine comprising a typewriter, a computer beneath the typewriter and controllable thereby, computer-operating mechanisms beneath said computer, and supporting lugs whereby said machine may be supported upon a stand, said cabinet comprising a casing for enclosing said operating mechanisms, said casing comprising a body-part and a cover-part, the cover-part being supported by said lugs and having an opening to permit the passage of the computer therethrough, and said body-part being mounted on said cover-part.

24. A sound-deadening cabinet for a machine comprising a typewriter, a computer beneath the typewriter and controllable thereby, computer-operating mechanisms beneath said computer, and supporting lugs whereby said machine may be supported upon a stand, said cabinet comprising a casing enclosing the operating mechanisms beneath said computer, said casing comprising a body-part, a cover-part, said cover-part being supported upon said lugs and having an opening to permit the passage of the computer therethrough, the upper edges of said body-part overlapping the lower edges of said cover-part, and fastening means passing through the overlapping edges to mount said body-part on the cover-part.

25. A sound-deadening cabinet for enclosing the noise-producing parts of a machine comprising a typewriter, a computer beneath the typewriter and controllable thereby, and computer-operating mechanisms beneath said computer, said cabinet comprising a casing for enclosing the operating mechanisms beneath said computer and comprising a body-part and a cover-part having an opening to permit the passage of the computer therethrough, means for supporting said cover-part upon said machine, and means for supporting said body-part on said cover-part.

26. A sound-deadening cabinet for enclosing the noise-producing parts of a machine comprising a typewriter, a computer beneath the typewriter and controllable thereby, a base for said computer, and computer-operating mechanisms beneath said base, said cabinet comprising a casing for enclosing said operating mechanisms and comprising a body-part, a cover-part having an opening to permit an operating connection between said computer and said operating

mechanisms, means for supporting said cover-part upon said base, means for supporting said body-part on said cover-part, and means for positioning said cover-part 5 relatively to said machine comprising abutments carried by said cover-part for engaging said base.

27. A sound-deadening cabinet for a machine comprising a typewriter, a computer 10 beneath the typewriter and controllable thereby, and computer-operating mechanisms beneath said computer, said cabinet comprising a main casing for enclosing the typewriter and computer, an auxiliary casing 15 for enclosing the operating mechanisms, said auxiliary casing comprising a body-part and a cover-part cut away to permit a connection to be established between the computer and the operating mechanisms, means 20 for supporting said cover-part upon said machine, means for supporting said body-part on said cover-part, means for positioning said cover-part relatively to said machine, and means carried by said cover-part 25 and engaging said main casing for positioning said main casing relatively to said auxiliary casing.

28. A sound-deadening cabinet for a machine comprising a typewriter, a typewriter-controlled computer beneath said typewriter, and controller-operating mechanisms beneath said computer, said cabinet comprising 30 a main casing for enclosing the typewriter and the computer, an auxiliary casing 35 enclosing the operating mechanisms beneath said computer and comprising a body-part and a cover-part, means for supporting said cover-part upon said machine, means for supporting said body-part on said cover-part, and means for positioning said cover-part relatively to said machine, said main casing having flanges whereby said main casing rests upon said auxiliary casing, and devices carried by said cover-part and engaging 40 said flanges for positioning said main casing relatively to said auxiliary casing.

29. A sound-deadening cabinet for a machine comprising a typewriter, a typewriter-controlled computer beneath the typewriter, 50 and operating mechanism beneath the computer and including a motor, means for connecting the motor to the computer, an upwardly-extending handle to control said connecting means, and a conductor to supply 55 current to the motor, said cabinet comprising a casing for said operating mechanism having an opening in the bottom thereof to accommodate said conductor, and an opening at each side of the conductor opening to permit 60 access to the operating mechanism, covers for the side openings, one of the side covers having a slot to receive said handle, and means to seal said slot around the handle.

30. A sound-deadening cabinet for enclosing the noise-producing parts of a computing machine, said machine having a typewriter portion, a computer portion, and various operating mechanisms beneath said computer portion, said cabinet comprising a casing for enclosing the operating mechanisms beneath said computer portion, said casing comprising a body-part and a cover-part, said cover-part having an opening 70 therein to permit the passage of the computer portion therethrough, said body-part being mounted on said cover-part.

31. A sound-deadening cabinet for enclosing the noise-producing parts of a computing machine, said machine having a typewriter portion, a computer portion, and various operating mechanisms beneath said computer portion, said cabinet comprising a casing for enclosing the operating mechanisms beneath said computer portion, said casing comprising a body-part and a cover-part, said cover-part being formed of sections 80 which can be applied to the machine from opposite directions, said sections when applied to the machine forming an opening 85 in which said computer portion is positioned.

32. A sound-deadening cabinet for enclosing the noise-producing parts of a computing machine, said machine having a typewriter portion, a computer portion, and various operating mechanisms beneath said computer portion, said cabinet comprising a casing for enclosing the operating mechanisms beneath said computer portion, said casing comprising a body-part and a cover-part, said cover-part being formed of sections 90 which can be applied to the machine from opposite directions, said sections when applied to the machine forming an opening 95 in which said computer portion is positioned, means for fastening said sections together, and means for mounting said body-part on 100 said sections.

33. A sound-deadening cabinet for enclosing the noise-producing parts of a computing machine, said machine having a typewriter portion, a computer portion, and various operating mechanisms beneath said computer portion, said cabinet comprising a casing for enclosing the operating mechanisms beneath said computer portion, said casing comprising a body-part and a cover-part, said cover-part being formed of a forward section and a rearward section, which 110 are applied to the machine from the front and rear, respectively, said sections when applied to the machine forming an opening in 115 which said computer portion is positioned.

34. A sound-deadening cabinet for enclosing the noise-producing parts of a computing machine, said machine having a typewriter portion, a computer portion, and various operating mechanisms beneath said 120

computer portion, said cabinet comprising a casing for enclosing the operating mechanisms beneath said computer portion, said casing comprising a body-part and a cover-part, said cover-part being formed of a forward section and a rearward section, which are applied to the machine from the front and rear, respectively, said sections when applied to the machine forming an opening in which said computer portion is positioned, said sections having overlapping portions, and fastening means passing through said overlapping portions.

35. A sound-deadening cabinet for enclosing the noise-producing parts of a computing machine, said machine having a typewriter portion, a computer portion, and various operating mechanisms beneath said computer portion, said cabinet comprising a casing for enclosing the operating mechanisms beneath said computer portion, said casing comprising a body-part and a cover-part, said cover-part being formed of a forward section and a rearward section, which are applied to the machine from the front and rear, respectively, said sections when applied to the machine forming an opening in which said computer portion is positioned, said sections having overlapping portions, said body-part having portions overlapping said sections, and fastening means passing through said overlapping portions.

36. A sound-deadening cabinet for a computing machine, said machine having a typewriter portion, a computer portion, various operating mechanisms beneath said computer portion, a stand, and supporting lugs whereby said machine may be supported upon said stand, said stand being open from front to rear, said cabinet comprising a casing for enclosing the mechanisms beneath the computer portion, said casing comprising a body-part and a cover-part, said cover-part being supported upon said lugs, said body-part being of a size to permit it to be applied to said cover-part by inserting it into the opening in the stand.

37. A sound-deadening cabinet for a computing machine, said machine having a typewriter portion, a computer portion, various operating mechanisms beneath said computer portion, a stand, and supporting lugs whereby said machine may be supported upon said stand, said stand being open from front to rear, said cabinet comprising a casing for enclosing the mechanisms beneath said computer portion, said casing comprising a body-part and a cover-part, said cover-part having an opening therein large enough to permit passage of the computer portion therethrough said cover-part being supported upon said lugs, said body-part being applied to said cover-part by inserting it into

the front of the opening in said stand and 65 moving it rearwardly therein.

38. The combination with a combined typewriting and computing machine having a typewriter with a keyboard, a computer, computer-operating mechanism under said computer, a support on which said computer rests and below which said mechanism is supported, and a signal to indicate the state of the computer, of sound-deadening means 70 comprising a lower casing having a top surrounding the base of the computer and overlying said support to be supported thereby and a bottom beneath said mechanism and connected with said top, and an upper casing comprising a body having back and side walls resting on the top of the lower casing and enclosing the rear and sides of the typewriter and the computer, a detachable front wall to close the front of the body around the keyboard and the front part of the computer and resting on the top of the lower casing, said front wall having a window through which the signal may be viewed, and a cover hinged to the body at the rear to close said body when in lowered 75 position.

39. Sound-deadening means for a machine comprising a typewriter having key-levers, a comb-plate in which said key-levers operate, and tabulator-keys, a computer beneath said typewriter, a computer case, said sound-deadening means comprising a casing having an opening through which the forward ends of said key-levers and the forward end of the computer case 80 are exposed, and a layer of sound-deadening material for closing the space between the typewriter and the computer case, said layer extending from said case to said 85 comb-plate.

40. Sound-deadening means for a machine comprising a typewriter having a keyboard and key-levers beneath said keyboard, a computer beneath said typewriter, and a computer case having a plurality of openings through which computer-operating devices extend to the exterior thereof, said sound-deadening means including a casing through which the keyboard and the forward part of the computer case project, a layer of sound-deadening material within said computer case for closing said openings, and an upward extension of said layer for closing said space between the typewriter and the computer case and around 100 the key-levers beneath the keyboard.

41. In combination with a machine of the class described, said machine comprising a typewriter section, a computer section, actuating means for the computer section, and various finger-pieces on said machine, and means to enclose said machine, provision being made in said means to enable the vari- 105 110 115 120 125

ous finger-pieces to be actuated from the exterior of the enclosing means.

42. Enclosing means for a machine of the class described, said machine comprising a typewriter section, a computer section under the typewriter section, and driving means under the computer section, said enclosing means comprising a sound-deadening casing to enclose the typewriter section and the computer section, and a sound-deadening casing to enclose the driving means.

43. Enclosing means for a machine of the class described, said machine comprising a typewriter section, a computer section under the typewriter section, and driving means under the computer section, said enclosing means comprising a sound-deadening casing to enclose the typewriter section and the computer section, a sound-deadening casing to enclose the driving means, and means to locate the casings relatively to each other.

44. A sound-deadening cabinet for a machine of the class described, said machine comprising a typewriter section, a computer section under the typewriter section, and actuating means under the computer section, said cabinet comprising a casing to enclose the typewriter section and the computer section, a casing to enclose the actuating means, and means to locate the cabinet relatively to the machine.

45. A sound-deadening cabinet for a machine of the class described, said machine comprising a typewriter section, a computer section under the typewriter section, and driving means under the computer section, said cabinet comprising a casing to enclose the typewriter section and the computer section, a casing to enclose the driving means, means to locate the second-named casing relatively to the computer section, and means to locate the first-named casing relatively to the second-named casing.

46. The combination with a machine of the class described comprising a computer section having register-actuating mechanism, an operating handle by which said actuating mechanism may be operated, a motor by which said actuating mechanism may be operated, and means including a finger-piece to disconnect the motor from said actuating mechanism when the latter is to be operated by said handle, of a sound-deadening cabinet for said machine having a slot through which said finger-piece may project to the exterior thereof, and so constructed that, in assembling the cabinet around the machine, the part containing the slot may readily be placed over said finger-piece.

47. A sound-deadening cabinet for a machine of the class described comprising typewriting mechanism having a keyboard and computing mechanism including a register located at the front of the keyboard, said

cabinet being provided with an opening through which the keyboard and the register extend and with means for effecting proper relative positioning between the machine and the cabinet.

70

48. A sound-deadening cabinet for a machine of the class described, said machine comprising typewriting mechanism having a keyboard section and a register located at the front of the keyboard, said cabinet comprising an upper section having a front wall and a lower section having a ceiling, said cabinet having an opening formed by a cut-out at the lower part of the front wall of the upper section and a cut-out at the forward part of the ceiling of the lower section, the register and the keyboard section of the machine extending through said opening.

75

49. A sound-deadening cabinet for a machine of the class described, said machine comprising a typewriter portion including a keyboard section, a computer portion having a register at the front thereof, said computer portion being arranged under the typewriter portion, and mechanism under the computer portion, said cabinet comprising an upper section and a lower section, the upper section having a front wall, the latter having a cut-out through which the keyboard section and the register may extend, said lower section having a ceiling, the ceiling having an opening therein through which the forward part of the computer section may extend, and means to support said cabinet on the machine.

80

50. The combination with a computer set-table to addition or subtraction, and a computer-controlling typewriter thereon having an addition-subtraction signal displayed at one point, of sound-deadening means comprising a casing for the typewriter having a window through which the typing may be observed and a separate small window independent of the first-named window as to permit the signal to be observed therethrough.

100

51. The combination with a typewriter and sound-deadening means therefor, of a computer having a case supporting said typewriter and having operative connections with the typewriter, means for deadening the sound of the computer comprising a layer of sound-deadening material between the typewriter and the computer provided with openings to accommodate said connections, the layer of sound-deadening material having slots to register with the openings in the computer, and a sound-deadening casing for a portion of said computer.

115

52. The combination with a combined typewriting and computing machine having a typewriter with a keyboard, a computer, computer-operating mechanism under said computer, and a stand for said computer, of sound-deadening means comprising a lower

120

125

130

casing open at the top to fit around the base of the computer and enclosing said mechanism, said lower casing being supported by said stand, and an upper sound-deadening 5 casing for said typewriter and said computer.

53. The combination of a typewriting machine, a support upon which said machine stands, motor-driving means under said 10 support, and sound-subduing means enclosing said typewriting machine and said motor-driving means, said enclosing means including a pan-shaped bottom closure mounted under said support.

15 54. The combination of a typewriting machine, a support upon which said machine stands, motor-driving means under said support, and sound-subduing means enclosing

said typewriting machine and said motor- 20 driving means, said enclosing means including a pan-shaped bottom closure mounted under said support, said bottom closure having an opening to give access to the motor and a cover to close said opening.

55. The combination of a typewriting machine, a stand to support said machine, said stand having a top to carry said machine, and having legs to support said top, means connecting said top and said legs, and a sound-deadening casing enclosing said typewriting machine and said top, and including a bottom closure beneath said top, said bottom closure having openings through which 30 extend the connections between the top and the legs.

JOHN WALDHEIM.
